UNITED STATES PATENT OFFICE

HAROLD H. GLASIER, OF LOS ANGELES, CALIFORNIA

MECHANICAL SPADER

Application filed June 3, 1929. Serial No. 367,914.

This invention relates to a tillage device which acts to break up the soil and to propel itself. It comprises broadly a combined spading and traction propeller having blades which are so arranged as to be forced into the ground, take hold thereof, and to act on the principle of an inclined plane. The spading and propulsion are caused by a reacting force opposite to the direction of propulsion and effected either by weight, motion in the opposite direction of a cooperating element or a slipping anchorage. It is the primary object of this invention to provide a tillage device of the above described character.

Other objects of this invention are to provide a tillage device having a combined traction and spading wheel or propeller and a cooperating earth gripping member, the wheel and member being disposed to exert a pincer action on the earth in a horizontal direction; to provide a tillage device having a set of combined traction and spading propellers, to provide a tillage device having a set of combined traction and spading propellers which are operable by oscillation of handles which may be effected by mechanical means or manually.

These objects together with other objects and corresponding accomplishments are obtained by means of the embodiments of my invention illustrated in the accompanying drawings, in which:

Fig. 1 is a side elevation of a manually operable device having a set of spading and traction propellers with movable anchorage members disposed to act as a pincer; Fig. 2 is a section as seen on the line 2-2 of Fig. 1; Fig. 3 is a section as seen on the line 3-3 of Fig. 2; Fig. 4 is a section as seen on the line 4-4 of Fig. 3; Fig. 5 is a side elevation of a manually operable device having a set of spading and traction propellers and a non-movable anchorage; Fig. 6 is a section as seen on the line 6-6 of Fig. 5; Fig. 7 is a plan view of the structure shown in Fig. 5; Fig. 8 is a section as seen on the line 8-8 of Fig. 6; and Figs. 9 and 10 are perspective views of bearings.

Referring more particularly to the drawings, Figs. 1 to 4 inclusive illustrate a pre-

ferred form of my invention. It consists of a hollow cylindrical body 15 made in substantially similar halves 15-a and 15-b, preferably castings. Each half has an upwardly extending hub 16 adapted to have a bar or pipe 17 secured therein to serve as an operating lever. Within the body is a ratchet wheel 18, adapted to be engaged by pawls 19-a and 19-b disposed within hubs 16. Threadedly secured in the ratchet wheel are shafts 20-a and 20-b, which extend through hubs in the ends of the body and have traction and spading propellers 22 mounted on their outer ends. Propellers 22 each consist of a hub preferably with three or more involute arms extending outwardly with a spader blade formed at their outer ends. The design renders assembly very simple. Each half of the body is slipped over the shaft in the spading wheel. The ratchet wheel is then engaged with the threads on both shafts, which threads are of opposite hands. The shafts are then screwed into the ratchet wheel until their ends meet, thus holding the two halves of the body together. The ratchet wheel can be centered between the propellers by backing either shaft out and screwing the other farther in. The direction of the threads is such that the action of the ratchet turning the propeller tends to screw each shaft in, but this tendency is opposed by the inside ends of the shafts abutting. Thus the propellers stay tight and can not bind the hubs on the ends of the body.

An ear 23 is provided on each half of the body and has attached to it a ground engaging arm 24 designed to assist in breaking up the soil and form an anchorage. Arms 24 are secured to ears 23 by bolts 25, teeth being provided on the ears and on the arms. Thus the depth that the arms penetrate the soil may be altered by loosening the bolt and swinging the arm about the bolt. The teeth prevent further movement when the bolt is tightened. Depending from each half of the body is a gauging arm 27, adjustable in a vertical direction and used to indicate the depth to which the spading arms are penetrating the soil.

The device is operated in the following manner: The operator stands at the front indicated by A in Fig. 1 face toward the machine, and grasps a lever 17 in each hand.

5 He pulls and pushes alternately upon these, which by means of the ratchet, causes the propellers 22 to revolve in the direction indicated by the arrow, and the machine to advance toward the operator who walks backward to keep ahead of it. The shape of the arms on the propellers is such they pull themselves into the ground when the forward movement of the propeller is resisted.

In Figs. 5 to 10, inclusive, is shown a modified design of spader. Propellers 30 are secured to a shaft 31 having a ratchet wheel 32 secured to it within a body 33 made in two parts 33—a and 33—b. Each half of the body has an operating arm 34 extending upwardly from it, and a breaking arm 35 extending rearwardly. These arms do not penetrate the soil as in the preferred form but serve to break any clods of earth that stick to the arms of the propeller.

25 Attached to shaft 31 and extending to the rear of the spader is a frame 37, shown dotted with several cultivators attached. This serves to further break up the soil and also as a drag or anchorage to make the propellers bite into the ground. The spader is operated in the same manner as the preferred form, the operator standing at B, Fig. 5, facing the levers 34, which are worked back and forth as before.

35 It will be noted that the propeller arms in addition to acting as an impeller, dig into the ground entering in a downward direction, then forcing the point gradually toward the rear. Finally the point starts upward 40 breaking and turning up the earth. In the preferred form shown in Figs. 1 to 4 the ground working arms in addition to acting as an anchorage, chop the turned up earth.

What I claim is:

45 1. A tillage device comprising a frame, a pair of propellers journalled on said frame and having involute shaped arms with spading surfaces, a pair of operating levers oscillatable on said frame, and one way clutch means connecting each lever to said propellers whereby the levers may be oscillated to and from each other to cause said propellers to be rotated.

55 2. A tillage device comprising a frame, a pair of propellers journalled on said frame and having involute shaped arms with spading surfaces, a pair of operating levers oscillatable on said frame, one way clutch means connecting each lever to said propellers whereby the levers may be oscillated to and from each other to cause said propellers to be rotated, and anchorage means disposed to follow said propellers penetrating the ground and create a drag on said device.

65 3. A tillage device comprising a frame, a

pair of propellers journalled on said frame and having involute shaped arms with spading surfaces, a pair of operating levers oscillatable on said frame, one way clutch means connecting each lever to said propellers whereby the levers may be oscillated to and from each other to cause said propellers to be rotated, anchorage arms disposed to follow said propellers, penetrate the ground and create a drag on said device, and means mounting said anchorage arms to cause them to alternately move toward the propellers in their ground engaging position.

4. A tillage device comprising a frame, a pair of propellers journalled on said frame and having involute shaped arms with spading surfaces, a pair of operating levers oscillatable on said frame, one way clutch means connecting each lever to said propellers whereby the levers may be oscillated to and from each other to cause said propellers to be rotated, anchorage arms disposed to follow said propellers, penetrate the ground and create a drag on said device, each of said anchorage arms being connected to a lever whereby to be caused to be moved alternately toward the propeller arms in their ground engaging position.

5. A tillage device comprising a frame, a pair of propellers journalled on said frame and having involute shaped arms with spading surfaces at their ends, a pair of operating levers oscillatable on said frame, one way clutch means connecting lever to said propellers whereby the levers may be oscillated to and from each other to cause said propellers to be rotated, a ground working tool having arms to dig into the ground and provide an anchorage dragging against said propellers, the ground working tool arms being mounted on said levers to be caused to be moved alternately toward the propeller arms in their ground engaging position whereby to exert a pincer action.

6. A tillage device comprising a frame, a pair of propellers journalled on said frame and having involute shaped arms with spading surfaces, a pair of operating levers oscillatable on said frame, one way clutch means connecting each lever to said propellers whereby the levers may be oscillated to and from each other to cause said propellers to be rotated, a ground working tool having arms to dig into the ground and provide an anchorage dragging against said propellers, the ground working tool arms being connected to said levers to be caused to be moved alternately toward the propeller arms in their ground engaging position whereby to exert a pincer action.

7. A tillage device comprising a frame, a pair of propellers journalled on said frame and having involute shaped arms with spading surfaces, a pair of operating handles oscillatable on said frame, pawl and ratchet

means connecting each handle to said propellers whereby the handles may be manually oscillated to and from each other to cause said propellers to be rotated.

- 5 8. A tillage device comprising a frame, a pair of propellers journalled on said frame and having involute shaped arms with spading surfaces, a pair of operating handles oscillatable on said frame, pawl and ratchet
10 means connecting each handle to said propellers whereby the handles may be manually oscillated to and from each other to cause said propellers to be rotated, and anchorage arms disposed to follow said propellers,
15 penetrate the ground and create a drag on said propellers.

9. A tillage device comprising a frame, a pair of propellers journalled on said frame and having involute shaped arms with spading
20 surfaces, a pair of operating handles oscillatable on said frame, pawl and ratchet means connecting each handle to said propeller whereby the handles may be manually oscillated to and from each other to
25 cause said propellers to be intermittently rotated, and anchorage arms disposed to follow said propellers, penetrate the ground and create a drag on said propellers, each of said anchorage arms being connected to a
30 handle whereby to be caused to be moved alternately toward the propeller arms in their ground engaging position.

In witness that I claim the foregoing I have hereunto subscribed my name this 27th
35 day of May, 1929.

HAROLD H. GLASIER.
